CLAIM

The ornamental design for a display screen, as shown and described.

DESCRIPTION

FIG. 1 is a front, right, top perspective view of the display screen showing our new design in a first state in which two portions of the display screen are overlapping with each other;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom plan view thereof;

FIG. 8 is front, right, top perspective view of the display screen in a second state in which the two portions of the display screen are beside each other and each portion is flat;

FIG. 9 is a front view thereof;

FIG. 10 is a rear view thereof;

FIG. 11 is a left side view thereof;

FIG. 12 is a right side view thereof;

FIG. 13 is a top plan view thereof;

FIG. 14 is a bottom plan view thereof;

FIG. 15 is a front, right, top perspective view of the display screen in a third state in which the two portions of the display screen are beside each other and each portion is curved;

FIG. 16 is a front view thereof;

FIG. 17 is a rear view thereof;

FIG. 18 is a left side view thereof;

FIG. 19 is a right side view thereof;

FIG. 20 is a top plan view thereof; and,

FIG. 21 is a bottom plan view thereof.

The dash-dash broken line showing in the figures is for the purpose of illustrating environmental structure and forms no
